US00D824674S

(12) **United States Design Patent** (10) **Patent No.:** **US D824,674 S**
Seiders et al. (45) **Date of Patent:** **** Aug. 7, 2018**

(54) **TRAY**

(71) Applicant: **YETI Coolers, LLC**, Austin, TX (US)

(72) Inventors: **Roy Joseph Seiders**, Austin, TX (US);
Andy Bondhus, Austin, TX (US);
Steve Charles Nichols, Austin, TX (US); **Andrew M. Bosway**, Austin, TX (US); **Tobias Hotchkiss**, Austin, TX (US); **Dennis Zuck**, Austin, TX (US)

(73) Assignee: **YETI Coolers, LLC**, Austin, TX (US)

(**) Term: **15 Years**

(21) Appl. No.: **29/595,332**

(22) Filed: **Feb. 27, 2017**

(51) LOC (11) Cl. **03-01**

(52) U.S. Cl.

USPC **D3/310**

(58) **Field of Classification Search**

USPC D3/303-315, 318-319, 328; D7/600.1, D7/601-602, 701

CPC B65D 1/00; B65D 1/34; B65D 1/36
See application file for complete search history.

Primary Examiner — Kelley Donnelly

(74) *Attorney, Agent, or Firm* — Banner & Witcoff, Ltd.

(57) **CLAIM**

The ornamental design for a tray, as shown and described.

DESCRIPTION

FIG. 1 is a top, front, right perspective view of a tray showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a top, front, right perspective view thereof shown in an alternate configuration.

The broken lines showing the remainder of the tray represent unclaimed subject matter and form no part of the claimed design.

1 Claim, 6 Drawing Sheets
